UNITED STATES PATENT OFFICE.

LOUIS E. WELSH, OF PHILADELPHIA, PENNSYLVANIA, ASSIGNOR, BY DIRECT AND MESNE ASSIGNMENTS, TO AMERICAN CONCRETE PILING COMPANY, OF PHILADELPHIA, PENNSYLVANIA, A CORPORATION OF PENNSYLVANIA.

PILE.

975,488.

Specification of Letters Patent. Patented Nov. 15, 1910.

Application filed February 20, 1909, Serial No. 479,142. Renewed September 26, 1910. Serial No. 583,912.

To all whom it may concern:

Be it known that I, LOUIS E. WELSH, a citizen of the United States, residing in Philadelphia, Pennsylvania, have invented 5 certain Improvements in Piles, of which the following is a specification.

My invention relates to concrete piles; and the object of my invention is to construct a pile with a substantially tapered cylindrical concrete shell which is first introduced into the ground and then filled with concrete; the whole, when the concrete is set, forming a solid homogeneous pile.

In the accompanying drawings: Figure 1, 15 is a sectional view of one form of pile made in accordance with my invention, and Figs. 2 and 3, are views illustrating modifications embodying my invention.

My improved pile is made up of a series 20 of sections or shells A of concrete which may be connected together in any suitable manner, and in the present instance rings of metal or other suitable material are interposed between the sections and have shouldered flanges receiving the ends of the sections.

As shown in Figs. 1 and 3, the sections or shells A are in the form of truncated cones, and their outer wall may be of any taper 30 desired, depending largely upon the soil into which the pile is to be driven. A driving point B is provided, which is preferably of the same diameter as the end of the concrete shell resting upon it, although, if desired, it 35 may be larger than the shell. The driving point has two annular seats b b', one within the other and separated in the present instance by a flange b², and as clearly shown in the drawings, the shell A rests upon the 40 seat b, while a tubular driving form C rests upon the seat b'. The driving form has a driving head D, with a portion d entering said driving form and serving to hold the form in a central position.

45 E represents a clamp ring, in the present instance made in two parts secured by bolts e, and this clamp ring is firmly secured to the driving form and holds the concrete shells against vertical movement. There 50 may be a space between the shell and the driving form, or it may fit snugly within said shell. Preferably the driving form is provided with annular ribs or shoulders c

to engage flanges carried by the rings interposed between the concrete shells.

In the structure shown in Fig. 1, the pile is made of a series of concrete sections A, separated by tapered rings B', of metal or other material, forming in effect a continuation of the tapered point B. In the use of 60 this pile, the brunt of the thrust in driving will be taken by the driving point and the metallic rings, but the load will be supported not only by the rings but also by the tapered pile sections. When the pile is completed by the filling of concrete, the rings 65 are embedded in the concrete and add strength to the structure.

In some instances a conical pile may be made up of a series of cylindrical sections 70 A', of an even diameter throughout, separated by rings B' tapered on the outer side, as illustrated in Fig. 2. In this instance, the driving point and the rings form the opening, and the shells simply follow.

In the structure shown in Fig. 3, a pile having a single taper throughout is shown, made up of a series of tapering concrete shells with rings B² of metal interposed between the same whose outer wall is in the 80 same plane as the concrete sections. All of the metal rings are of substantially the same construction internally so that the same kind of a driving form may be employed to enter them into the ground.

The operation of forming my improved pile is as follows: Tubular concrete sections of the desired taper are mounted on a driving form such as illustrated in Figs. 2 and 3 and entered into the ground; the initial 90 pressure being taken by the driving point and form while the pressure due to the enlargement of the pile is taken by the concrete shells. These shells are reinforced and made of such diameter that they can withstand this pressure. After the shells have been entered into the ground, the driving form is removed, leaving the shells and point section within the ground, and then the pile 95 can be inspected.

The point of the pile may remain in the ground, and may be either solid, as illustrated in the drawings, or it may be of the type illustrated in my application for patent filed December 29, 1908, Serial No. 469,834. 105 In large piles using points having a detach-

able portion, as disclosed in my application last above mentioned, such portion of the point may be removed, and if it has reached bed-rock a portion of the earth under the 5 point can be removed and the space so made prepared for the reception of concrete mixture. The concrete mixture is then placed in the shells in any suitable manner, and when the pile is completed it will be a substantially 10 tapered solid homogeneous mass of concrete such as shown in Fig. 1, or its outer contour may be like Figs. 2 and 3.

My improved pile is particularly adapted for use in soil having an under strata of 15 quicksand above bed-rock, and where it is not desired to drive through such quicksand onto bed-rock. By the use of my invention, a pile can be driven into the upper strata which has good supporting qualities and 20 firmly held therein; the surface friction on the pile, owing to its conical shape, sustaining the load carried by the pile.

While I prefer to make the point section of metal, steel, for instance, it may be made 25 of reinforced concrete if desired, and any suitable reinforcing members may be in-

serted in the space inclosed by the shells after the latter have been driven in order to add strength to the body of the pile.

I claim:

1. A pile having a driving point, a series of concrete shells, a series of rings interposed between the shells, and a body of concrete filling the center of the pile.

2. A pile having a driving point, a plurality of concrete shells, a series of rings increasing in diameter from the point and separated by said shells, and a body of concrete filling the center of the pile.

3. A pile having a driving point, a series of concrete shells successively increasing in diameter from the point, a series of rings separating said shells, and a body of concrete filling the center of the pile.

In testimony whereof, I have signed my name to this specification, in the presence of two subscribing witnesses.

LOUIS E. WELSH
